(57) **CLAIM**

The ornamental design for a carafe, as shown and described.

DESCRIPTION

FIG. 1 is a front perspective view of a carafe according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof;

FIG. 9 is a front perspective view showing an example use thereof; and,

FIG. 10 is an enlarged view of region 10 in FIG. 9.

The curved diagonal shading indicates a transparent surface. The broken lines shown in the drawings illustrate portions of the carafe that form no part of the claimed design or environmental structure that forms no part of the claimed design.
